DESIGN FOR A DRAWER PULL

Lawrence L. Rosenthal, Los Angeles, Calif.

Application September 14, 1945, Serial No. 122,089

Term of patent 3½ years

(Cl. D10—8)

To all whom it may concern:

Be it known that I, Lawrence L. Rosenthal, a citizen of the United States, residing at Los Angeles, in the county of Los Angeles and State of California, have invented a new, original, and ornamental Design for a Drawer Pull, of which the following is a specification, reference being had to the accompanying drawing, forming part thereof.

The drawing illustrates a drawer pull embodying my new design in which Fig. 1 is a top plan view; Fig. 2 is a side elevational view; Fig. 3 is a perspective view; and Fig. 4 is an end elevational view.

I claim:

The ornamental design for a drawer pull, as shown.

LAWRENCE L. ROSENTHAL.
